UNITED STATES PATENT OFFICE.

LYNN J. GRACE, OF CHICAGO, ILLINOIS, ASSIGNOR OF ONE-HALF TO JOHN E. BELL, OF CHICAGO, ILLINOIS.

EDGE SETTER AND BURNISHER.

Application filed August 13, 1920. Serial No. 403,260.

To all whom it may concern:

Be it known that I, LYNN J. GRACE, a citizen of the United States, residing at Chicago, in the county of Cook and State 5 of Illinois, have invented certain new and useful Improvements in Edge Setters and Burnishers, of which the following is a specification.

The invention relates to a combined edge 10 setter and sole burnishing device for use in the manufacture of shoes.

One of the objects of the invention is to provide a burnishing device for burnishing or polishing the edge parts and the soles of 15 shoes.

Another object is to provide a means for heating the device and for maintaining the temperature thereof substantially constant.

Another object is the provision of adjusting means and an indicator therefor, for adjusting the edge setter for soles of different thicknesses.

Further and more specific objects of the invention will become readily apparent to 25 persons skilled in the art from a consideration of the following description taken in conjunction with the drawings, wherein:

Fig. 1 is a side elevation of the device showing the parts in section;

Fig. 2 is an end view in elevation, and;

Fig. 3 is a transverse section taken on line 30 3-3 of Fig. 1.

In all the views the same reference characters are employed to indicate similar parts.

The cylinder 5 is the roll, or polishing surface, to be heated and used for polishing soles, and edges of the soles, of shoes. In this particular instance the roll, or cylinder is to be heated by electricity.

A cylinder heating means is placed on the inside of the cylinder 5 and supported by an insulating disk, 7 and 8, at each end. The heating element may, therefore, be bodily slipped into the cylinder, or roll 5, or taken therefrom without disturbing any of the connections.

A wire of sufficient size for heating the cylinder and its parts is wound about the cylinder 6 into a coil 9 for connection between terminating binding posts 10 and 11, located on the insulating disks 7 and 8, respectively. The electricity may be brought to the device by the wires 12 and 13 which are connected to the respective binding posts.

Inside of the cylinder or tube 6 is a thermo responsive device, 14, consisting of an insulating base, 15, and an expansion bar 16. The bar is secured to the base under the binding post 17, at one end, and is free to make contact with the terminal 18 at the other end. When the bar is heated to a temperature above the temperature to be maintained on the outside of the cylinder 5, it expands into the position shown in dotted lines, and thereby opens the heating circuit, when the cylinder cools the bar closes the circuit.

The binding post 11 is directly connected by the wire 20 to the binding post 17, while the contact 18 is connected by the binding post 21 and wire 22 to the end 23 of the heating coil 9. The other terminal of the heating coil is connected direct to the binding post 10. By this arrangement the thermo-responsive device and the heating coil are placed in series circuit with each other, so that when the circuit is opened by the thermo-responsive device the current will no longer flow through the heating coil. The current controlling device in the tube 6 is substantially sealed therein and no drafts of air can pass through the tube and affect the thermo-responsive device, and, therefore, the temperature of cylinder 5 is maintained substantially constant, and not modified by outside influences.

One end of the cylinder 5 is out turned to provide a bead 24 which is a part of the edge of the end surface of the cylinder. Located upon the cylinder 5 is a slidable ring 25 having a suitable surface 26, co-operating with the bead 24. The arrangement is such that the surface 26 may be adjusted axially with reference to the bead 24 by a handle 27, to provide the proper space between the parts 24 and 26 to compensate for soles of different thicknesses.

Around the sleeve 25 is a support, 28, slidable with the sleeve and operable by a handle 27.

A short shaft 30 carries on its inner end a miter gear 31. The handle 27 is secured to the shaft 30, as by a pin 32, or otherwise. The gear 31 is in mesh with a miter pinion 33 which is fixed on the end of the rotatable shaft 34. The shaft 34 is threaded as at 35, and the bearing 36 is threaded for the shaft. Collars 37 and 38 prevent axial movement of the shaft 34, so that when the

shaft 34 is rotated the standard 36 of the support 28 associated with the sleeve 25 is moved axially of the cylinder 5, so that the space between the annular bead 24 and the 5 end 26 of the sleeve 25 may thus be varied for the purpose desired.

Rotating with the stub shaft 30 is an index, or pointer, 40, which is moved over index, or pointer, 40, which is moved over a scale 41, on the disk 42, when the handle 10 27 is rotated. This will indicate relatively at all times the distance between the parts 24 and 25. The support 28 is provided with two legs, 43 and 44, which ride along the shafts 34 and 45, when the handle 27 is 15 rotated. A stationary support 46, provided with an upstanding leg 47 is connected to the insulating disk 7, as by rivets 48 or the like. This end of the cylinder 5 is also provided with an outstanding annular bead 20 49, which may be either larger or smaller than the bead 24, and in some instances may be advantageously used without the bead 24 or the ring 25.

When the surface of the cylinder is heated 25 by the heating medium, the shoe soles are polished by rubbing them energetically over the surfaces of the cylinder 5 or the beads 34 and 49, and in contact with the surface 26 of the ring 25, which operation will be 30 readily understood by persons skilled in the art.

Having described my invention what I

claim as new and desire to secure by Letters Patent is:

1. A device for burnishing the surfaces 35 of shoe soles, having in combination a fixed non-rotatable outer cylinder provided with an outwardly extending bead; a ring slideable on the cylinder providing a surface to form with the bead an adjustable edge 40 setter, means to axially adjust the ring with respect to the bead; an inner cylinder; means for heating the cylinders; and a heat responsive device within the inner closed cylinder to automatically maintain the temperature of the outer cylinder substantially constant.

2. A device for burnishing the surfaces of shoe soles having in combination a fixed 50 non-rotatable outer cylinder provided with an outwardly extending bead; a ring slideable on the cylinder providing a surface to form with the bead an adjustable edge setter; means to axially adjust the ring with respect to the bead; a closed cylinder within 55 the outer cylinder; a dial and index to indicate the extent of the adjustment; and a heating device between the cylinders and a temperature controlling device within the inner cylinder and removable therewith as 60 a single unit.

In testimony whereof I hereunto subscribed my name.

LYNN J. GRACE.
